UNITED STATES PATENT OFFICE.

OLIVER J. LA BAIE, OF BUFFALO, NEW YORK.

WHIFFLETREE-COUPING.

SPECIFICATION forming part of Letters Patent No. 439,802, dated November 4, 1890.

Application filed July 24, 1890. Serial No. 359,743. (No model.)

To all whom it may concern:

Be it known that I, OLIVER J. LA BAIE, of Buffalo, in the county of Erie and State of New York, have invented certain new and useful Improvements on Whiffletree-Couplings; and I do hereby declare that the following description of my said invention, taken in connection with the accompanying sheet of drawings, forms a full, clear, and exact specification, which will enable others skilled in the art to which it appertains to make and use the same.

This invention has general reference to improvements in whiffletree-couplings; and it consists, essentially, in the novel and peculiar combination of parts and details of construction, as hereinafter first fully set forth and described, and then pointed out in the claims.

In the drawings already referred to, Figure 1 is a plan of a thill and whiffletree employing my invention. Fig. 2 is a plan of my device. Fig. 3 is a longitudinal sectional elevation in line Y Y of Fig. 2 and illustrating the means of attachment to the whiffle and cross tree. Fig. 4 is a plan of my device, showing the plates swung apart. Fig. 5 is a longitudinal sectional elevation of a modification of my device.

Like parts are designated by corresponding letters of reference in all the figures.

The object of this invention is the production of a suitable whiffletree-coupling that can be cheaply produced, and which can be readily fastened to the whiffle and cross tree of the thills, and at the same time to provide means whereby the whiffletree may be detached without loosening the device, it being a further object to produce a device in which bolts as a connecting mechanism are entirely dispensed with. To attain this result I construct my coupling as illustrated in the several figures of the drawings, and in which—

A represents the thills, and A' the cross-tree thereof, A'' being the whiffletree to which my device is applied.

B, Figs. 2, 3, 4, and 5, represents the lower plate of my coupling, and which is attached to the cross-tree of the thills by screws passing through apertures b b in said plate and into the tree, as shown in Fig. 3. This plate is provided at its rear extremity with a down-

wardly-pendent flange C, which has apertures for the reception of screws, and with a curved protuberance or boss C', within which and passing vertically through the same is a circular aperture c, having a longitudinal groove c'. At the opposite extremity of this plate, and on the upper surface thereof is provided a projection D, extending across the face of the same and having its inner or rear edge of the curvature of an arc of a circle having its center in the center of the aperture c in the boss C'. This edge is provided with a groove d of proper dimensions, following the line of curvature of the same.

Over the plate B, hereinbefore referred to, fits a plate B', which is fastened to the whiffletree A'' by means of screws g, Fig. 3, passing through apertures e e, Fig. 4, and at its rear extremity a downwardly-pendent pintle or pivot F, corresponding in size with the aperture c in the boss C' of the plate B, in which it is adapted to fit. This pintle has at its lower extremity a nose f, fitting the groove c', and which is so arranged on said pintle that when the plates are directly over each other, as in Fig. 2, the said nose will be diametrically opposite the groove c' in the aperture c, so that when the parts are in this position they are securely locked together, but at the same time may be removed from each other by revolving one of the plates one-half revolution and withdrawing the pintle from the aperture. The plate B' is provided near its forward extremity with a projection d', fitting the groove d, so that all strain brought upon said plate B' will be received and taken up by the boss D. At the forward extremity of the plate B' is located an upwardly-projecting flange E for the reception of screws to fasten the same to the whiffletree.

This device has numerous advantages over the usual bolt mechanism, some of which may be enumerated as follows: First, it can more readily be attached, as well as detached, from the thills than the usual devices now used; it is more accessible for oiling when necessary, a matter which is now impossible, or nearly so, in using the present devices; it provides for a stronger whiffletree, it not being necessary to perforate the same for the insertion of the bolt, as well as a much neater one, and it

further obviates the oscillating motion of the tree caused by the motion of the horse.

In Fig. 5 I have illustrated my device as employing a differently shaped groove. Such 5 a change would not in any way differ from the nature and spirit of my invention.

It is obvious that there is no strain whatever upon the pintle F, it being all received and taken up by the upper plate bearing 10 against the lower one at the groove d. The only function and office of the pintle F is to act as a pivot for the upper plate and to hold the parts together. It is evident that the purpose of the groove d is to prevent the upper 15 plate B' from being lifted off from the lower plate B, and thereby injuring the device.

This device, as hereinbefore described, can be produced in malleable iron or brass in the process of casting, or of wrought metal by 20 drop-forging, the parts requiring accurate fitting may be milled upon a suitable milling machine, and the whole when finished can be nicely japanned or nickel or silver plated, thereby producing a very efficient and hand- 25 some addition to the thills of buggies, carriages, and the like, and one which can be produced at a very low figure.

Having thus fully described my invention, I claim as new and desire to secure to me by Letters Patent of the United States—

1. The combination, with the plate B, having the apertured projection and flange at its rear extremity and the grooved projection on its upper surface, of the plate B', having the projection on its lower surface engaging said 35 grooved projection, and the pivot at its rear extremity formed integral with said plate B' and engaging said apertured projection, in a manner substantially as set forth.

2. The combination, with the plate B, having the projection D and groove d, the projection C', having the aperture c and groove c', and the flange C, of the plate B', having the flange E and groove d', the pivot F, and nose f, substantially as and for the purpose 45 set forth.

In testimony that I claim the foregoing as my invention I have hereto set my hand in the presence of two subscribing witnesses.

OLIVER J. LA BAIE.
